Attorney

UNITED STATES PATENT OFFICE.

JACOB P. THOMAS, OF SAN JOSE, CALIFORNIA.

VALVE CONTROLLING OR LOCKING MEANS.

Application filed June 28, 1922. Serial No. 571,834.

To all whom it may concern:

Be it known that I, JACOB P. THOMAS, a citizen of the United States, residing at San Jose, in the county of Santa Clara and State 5 of California, have invented certain new and useful Improvements in Valve Controlling or Locking Means, of which the following is a specification.

This invention relates to a valve controlling or locking means for a petcock carried upon the transmission casing of an automobile such as an automobile of the Ford type.

Another object of this invention is the 15 production of a simple and efficient locking means for holding the petcock in a closed position and preventing the same from jar-ring open.

Other objects and advantages of the 20 present invention will appear throughout the following specification and claims.

In the drawings:

Figure 1 is a side elevation of a portion of the automobile showing the petcock locking 25 means applied thereto.

Figure 2 is a transverse sectional view through a portion of the automobile, showing the locking means for the petcock.

Figure 3 is a top plan view of the structure shown in Figure 2.

By referring to the drawings it will be seen that 1 designates the body of the automobile of any suitable or desired character or design, which supports the usual transmission casing 2. The usual form of petcock 3 is mounted upon the transmission casing 2 and the usual turning or finger grip 4 is carried thereby. An operating rod 5 is pivotally connected to the finger grip or operating key 4, and the outer end of the rod 5 carries a pivotally connected operating blade 6. This operating blade 6 is adapted to be swung into and out of the knife clamp 7, which clamp is secured to the running board as indicated at 8 by means of a suitable clamping nut 9. The knife clamp 7 comprises a pair of clamping jaws 10, between which clamping jaws 10 is adapted to be swung the operating blade 6.

By considering Figure 2 of the drawings it will be seen that by swinging the blade 6 out of engagement with the knife clamp 7, the rod 5, which extends through the aperture 11 formed in the running board, may be

rotated for the purpose of opening the drain 55 cock 3. In this way it will be seen that it is unnecessary for the operator of the car to climb under the car in order to operate the drain cock. It will be further understood that a very simple and efficient means has 60 been produced for locking the drain cock in a closed position, thereby preventing the drain cock from being accidentally jarred to an open position.

It should be further understood that certain detailed changes in mechanical construction may be employed in the present device without departing from the spirit of the invention, so long as these changes fall within the scope of the appended claims. 70

What is claimed is:

1. In combination with a petcock having an operating key, of an operating rod pivotally connected to the key, an operating blade pivotally connected to the outer end of 75 the rod, and a knife clamp adapted to receive the blade and hold the rod in a set position against rotation.

2. In combination with a petcock of the class described, provided with an operating 80 key, of an operating rod, the operating rod being adapted to extend through the running board of an automobile, an operating blade pivotally connected to the outer end of the rod, a clamp adapted to be supported in engagement with the running board of an automobile and adapted to receive the operating blade when the same is swung downwardly into engagement with the clamp for locking the rod against rotation. 90

3. As a new article of manufacture, an operating device for valves comprising an elongated operating rod, means formed on one end of the rod for engaging a valve stem, a flat blade pivotally secured to the 95 outer end of the operating rod, and a resilient knife clamp rigidly secured below the operating rod and in the path of the operating blade, when the rod is in one position, whereby the blade can be moved into engagement with the resilient clamp and the rod held against accidental rotation. 100

In testimony whereof I affix my signature in presence of two witnesses.

JACOB P. THOMAS.
